UNITED STATES PATENT OFFICE.

CLYDE C. GAULT, OF WOOSTER, OHIO.

DESIGN FOR AN INFLATED TOY ALLIGATOR.

Application filed October 5, 1928. Serial No. 28,384. Term of patent 7 years.

To all whom it may concern:

Be it known that I, CLYDE C. GAULT, a citizen of the United States, residing at Wooster, in the county of Wayne and State of Ohio, have invented a new, original, and ornamental Design for an Inflated Toy Alligator, of which the following is a specification, reference being had to the accompanying drawing, forming a part thereof, in which the figure is a side view of an inflated toy alligator, showing my new design.

I claim:

The ornamental design for an inflated toy alligator substantially as shown.

In witness whereof I hereunto set my hand this 6 day of June, A. D. 1928.

CLYDE C. GAULT.
